UNITED STATES PATENT OFFICE.

JOHN F. LEWIS, OF SAN FRANCISCO, CALIFORNIA.

DISPENSING DEVICE.

Application filed December 7, 1920. Serial No. 428,858.

To all whom it may concern:

Be it known that I, JOHN F. LEWIS, a citizen of the United States, residing at San Francisco, in the county of San Francisco and State of California, have invented new and useful Improvements in Dispensing Devices, of which the following is a specification.

This invention relates to a dispensing device and particularly pertains to a device from which cards or similar articles may be dispensed.

It is the principal object of the present invention to provide a device of simple construction and operation from which cards or like articles may be successively dispensed from a stack of the articles within a container by successive manual movement.

The present invention contemplates the use of a container within which a stack of articles may be disposed, said container being equipped with a manually operated ejector by which the lowermost article in the stack may be projected through a dispensing opening in the side of the container.

The invention is illustrated by way of example in the accompanying drawings, in which:

Figure 1 is a view in vertical section and elevation showing the device with which the present invention is concerned.

Fig. 2 is a view in section showing the device as seen on the line 2-2 of Fig. 1.

Fig. 3 is a view in vertical section as seen on the line 3-3 of Fig. 1.

Fig. 4 is a view in perspective showing the assembled device.

Broadly considered, the present invention comprises an outer housing 10 formed with a lower compartment 11, and a container 12. The lower compartment is adapted to accommodate the operating mechanism required by the device, while the upper compartment is designed to accommodate a stack 45 of articles to be dispensed, as for example, the stack of articles indicated at 13 in Fig. 1. The housing is formed with a vertical front wall 14, through which a dispensing opening 15 is made, this wall being secured to side walls 16 and 17, held in spaced relation to each other by a cross wall 18 and a floor 19. It will be noted that the compartment 12 is of smaller dimensions than the length of the compartment 11, thus making 55 the narrow cross wall 18 necessary. The top of the compartment 12 is formed with a per-

manent cover 21, while the back of this compartment is provided with a hinged wall member 22. The back of the compartment 11 is closed by a hinged door 23, both members 22 and 23 are formed with lock fingers 24, by which the doors are frictionally held in position. These doors separately provide access to compartments 11 and 12, respectively.

Extending horizontally within the housing 10, and at a desirable point below the compartment 12, is a false floor 25, carrying the dispensing mechanism. This floor is supported on brackets 26, as shown in Fig.

70 3, and is furthermore formed with a central longitudinal slot 27.

In order to facilitate the assembling of the machine, the slot 27 is enlarged at its ends as indicated at 28 and 29 of Fig. 2. The top surface of the false 75 floor 25 is in alignment with the lower edge of the dispensing opening 15, thus insuring that the lowermost article to be dispensed may be passed directly off of the floor and through the opening. The width of this 80 opening is considerably wider than the thickness of the article to be dispensed, and it is therefore necessary to provide an adjusting plate 30 to prevent more than one of the articles from passing out through the 85 opening at a time. This adjusting plate is more clearly shown in Fig. 3, where it will be seen to have screws 32 extending through parallel slots in the plate, and by which it

may be vertically adjusted and locked. The 90 screws extend into a false front wall 33, which has been provided to adjustably accommodate articles of various sizes. Angle members 34 are secured at the back of the dispensing compartment 12 and firmly hold 95 the pack 13 in its stacked position.

Mechanical means are provided for ejecting the lowermost cards from the pack. This comprises a reciprocating ejector 35. The ejector is formed by a cross head 36, carrying a finger 37. The cross head is horizontally slidable along parallel guideways secured to the under face of the false floor 25. The finger 37 is secured midway the length of the cross head, and is formed with an upturned portion 39, extending through a longitudinal slot 27 of the floor. The forward end of member 39 is turned down in order to remain out of engagement with the articles to be dispensed. A transverse shoulder 40 is formed across the member 39 by a plate 41. This shoulder is adapted to en-

gage the rear edge of an article to be dispensed and to force the article forwardly as the ejector moves. Attention is directed to the fact that the finger 37 is pivoted to the cross head 36 on a pin 42.

The pivotal movement of the finger 37 is provided to allow the finger to move into engagement with the lowermost article in the stack and to fall away from the stack after this article has been ejected. This action is brought about by extensions 43 formed by continuations of the plate 41. These extensions overhang the sides of the longitudinal slot 27 and pass from supported positions thereon when the ejector 35 reaches its foremost movement, and the members 43 fall through the enlarged opening 28 in the end of the slot 27. At this time the finger 37 will fall down upon a connecting link 44, which will be hereinafter described. When the ejector moves to the extreme rear stroke the finger 37 will be engaged by a spring 45, and will be lifted up through the slot 27 with the projections 43 being lifted through the enlargement 29 at the end of the slot. The spring is sufficiently long to hold the projections 43 above the enlargement 29 until after the ejector has moved forward to a position where the projections 43 will rest upon the floor at the sides of the slot 27, thus being rigidly held relative to the stack of articles being dispensed.

Reciprocal movement of the ejector 35 is manually brought about by an operating lever 46. This lever may be oscillated at the side of the box as supported upon a shaft 47. The shaft 47 has its bearings in the side walls 16 and 17 of the housing. The operating lever 46 is rigidly secured to the shaft and is adapted to swing an arm 48, which arm is adapted to swing a lever 49 forwardly. This lever is pivotally secured to the connecting link 44, carried by the ejector 35. The arm 49 is freely pivoted upon the shaft 47, and is fitted with a tension arm 50 to which a coil spring 51 is fastened. The opposite end of this coil spring is secured within the housing, and acts to restore the arm automatically after the actuation by the operating lever 46. Pins 52 limit the movement of the operating lever 46, as shown in Fig. 4.

It will thus be seen that by the device here disclosed, a plurality of like articles may be successively and singly dispensed from a container by successive manual movement, said device being designed to accommodate articles of various dimensions, and to further operate in a simple manner by a mechanism which is not liable to require repair.

While I have shown the preferred form of my invention as now known to me, it will

be understood that various changes might be made in the combination, construction and arrangement of parts by those skilled in the art, without departing from the spirit of the invention as claimed.

Having thus described my invention, what I claim and desire to secure by Letters Patent is:

1. A dispensing device comprising a container within which a stack of identical articles to be dispensed may be disposed, said container having a horizontal slot in its front wall, a false floor within the container, with its upper face in horizontal alignment with the lower edge of the opening, a longitudinal slot formed in said floor, said slot being enlarged at its ends, over which slot the articles to be dispensed are disposed, an ejector adapted to move forwardly along said slot and to engage the rear edge of the lowermost article in the stack, and means on the ejector adapted for supporting it from the floor during its forward movement and adapted to pass through the floor at the enlarged ends of the slot whereby the return stroke of the ejector will take place below the floor, means for raising the ejector above the floor at the end of the return stroke, and manually operated means for moving said ejector forwardly and means for automatically returning the same to its original position.

2. A dispensing device comprising a container within which a stack of articles to be dispensed may be disposed, said container having a horizontal dispensing slot through its front wall, means for adjustably determining the width of said slot to agree with the dimensions of the article dispensed, a false floor within said container, disposed with its upper face flush with the lower edge of the slot, said floor being formed with a slot longitudinally thereof, the ends of the slot being enlarged and over which slot a stack of articles to be dispensed is supported by the floor, an ejecting finger adapted to move forwardly along said slot and to project therethrough to engage the lowermost article of the stack and carry it therewith, means upon said finger for supporting it from the floor during its forward movement, and adapted to pass through the floor at the enlarged ends of the slot whereby the return stroke of the ejecting finger will take place below the floor, spring means for lifting the finger supporting members through the opening in the rear end of the slot at the completion of the return stroke of the ejecting finger, manual means for moving said ejecting finger forwardly to dispense the articles and spring means for returning the finger to its original position.

JOHN F. LEWIS.
